UNITED STATES PATENT OFFICE

HENRY McLAREN, OF LEEDS, ENGLAND

PLOW OPERATED BY STEAM OR OTHER MOTIVE POWER

1,018,252.

Specification of Letters Patent.

Patented Feb. 20, 1912.

Application filed September 23, 1909. Serial No. 519,174

To all whom it may concern:

Be it known that I, HENRY McLAREN, a subject of the King of Great Britain and Ireland, of Midland Engine Works, Leeds, in the county of York, England, have invented new and useful Improvements in Plows Operated by Steam or other Motive Power, of which the following is a specification.

- 10 This invention relates to improvements in plows operated by steam, or other motive power, on what is known as the direct traction method, and has for its object to provide such plows with improved means for
- 15 raising the plows from the soil and holding them in that position and for lowering them to their work and regulating their depth of work, and for raising and lowering the subsoilers, in plows in which subsoilers are
- 20 used, and providing other improvements as hereinafter explained.

It is necessary for the plows and sub-soilers to be lifted out of the soil at the ends of the furrows to admit of the engine 25 and plows turning around and to reenter the ground on the return journey. Hitherto this lifting has been usually done by levers operated by hand, which necessitates heavy manual labor and loss of time, and, in the 30 case of heavy plows, for deep work, it is impossible to lift many plow heads at one time. Mechanical lifts operated by steam, and other, power have been used and worked from the engine, but they are costly and 35 complicated and not suitable for operation by the unskilled laborer usually in charge of plows.

According to my invention the plows (and subsoilers when used) are made self-lifting, the attendant when it is desired to lift them, simply throwing over a tumbling lever which brings all the plows (and subsoilers when used) to the surface without further manual labor, so that one attendant can operate a large number of plows, or plows and subsoilers, without delay, or stoppage, of the engine.

We will take a four-furrow plow as a convenient one for description, but the invention is not limited to that number. If the land be level, good work may be done with a large number of plows attached to a single frame, but where the surface of the ground is uneven it is not desirable to have many plows attached to one frame. It is preferred to use two, or more, frames with

but a few plows on each frame, as then each frame follows the surface over which it passes, and the work is better done and the depth kept more even.

Figures 1 and 2 are an elevation and a plan respectively of a four-furrow plow (without subsoilers) constructed according to this invention; Fig. 3 is a plan showing a series of three sets of plows connected together and to the engine; Figs. 4 and 5 show, in elevation and plan respectively, the means for retaining the plows in their raised position, and for adjusting the intermediate wheel; Fig. 6 is an elevation showing the arrangement of the subsoilers in a plow; Fig. 7 shows in elevation the means for raising and lowering the subsoilers. 65 70

The plows 1 are carried on a frame 2 supported by three wheels, the forward wheel 3 traveling in the furrow left by the last plow on the previous round, the hinder wheel 4 running in the furrow left by the last plow of the series, and the intermediate wheel 5 running on the surface of the unplowed land. The forward and hinder wheels 3 and 4 are each mounted on an inclined arm 6 at the lower end of a vertical spindle 7, as shown in Fig. 3, and each of the said wheels is adjustable vertically, so that, when the plows are not in action, but are traveling on the road, the said wheels are set lower than the bottom cutting edges of the plow shares and keep them clear of the road, but when plowing, the underside of each of these wheels runs approximately level with the cutting edges of the plow-shares. The said arms 6 are inclined downward so as to throw the said wheels 3 and 4 out of the perpendicular and bring the lower portions of their suitably inclined rims into the corner of the furrow, as shown in Fig. 3, to take the side thrust of the plows in the usual manner.

frame 2. The vertical adjustment of the forward wheel 3 is effected by means of a screw (not shown) on the upper end of the vertical spindle 7, and a screw-nut confined in a pocket 15, cast in the spindle bracket 16, carried by the frame 2, so as to be rotatable therein, and is operated by any suitable device, such, for example, as a spur pinion 17 (see Fig. 1) on a spindle 18, carried in bearings projecting from the bracket 16 and provided with a handle 19. This provides a satisfactory and direct method of carrying the front end of the plow on the vertical spindle 7. The steering hand lever 9 is only necessary when working a single set of plows, or on the first of a series of sets of plows. It enables the attendant to steer the plow, or plows, around the headland and bring the forward wheel 3 into the return furrow should the engine be out of line. When the first plow is properly entered in the furrow, the steering hand lever 9 is fixed by the catch 11, and catch plates 12. Each of the following sets of plows is automatically steered by the preceding set of plows, and will enter the respective furrow without further attention from the attendant.

The coupling of the sets of plows to the engine and to each other can be effected as illustrated in Fig. 3 as applied to three sets of plows in series. The first whiffle-tree 25 is attached, at its inner end, to the drag-plate 26 of the first set of plows; the second whiffle-tree 27 is attached in the same manner to the second set of plows, the outer end of the first whiffle-tree 25 being coupled, by a steel rope, or the like, 28, to the center of the second whiffle-tree 27, which, in turn, is coupled from its outer end, by steel rope, or the like, 28, to the drag-plate 26 of the next set of plows, and so on if more sets of plows be used. The engine (part of which is seen at 29) is coupled to the first whiffle-tree 25 at a point giving the proper leverage to obtain an equal pull on all the sets of plows of the series.

The frames of the sets of plows are hinged together by hinge links 30 which keep the sets of plows properly spaced from each other under all conditions of working. When a set of plows is lifted from its work, the pull becomes slight, and it would immediately overrun the other set, or sets, of plows to the limit of the whiffle-trees if not prevented by the link 30, which is arranged to allow either plow to lift without disturbing the other, or others. This can be arranged as follows:—A horizontal pivot 31 is fixed to the frame of the leading set of plows. One end of the hinge link 30 is hung to this pivot 31, the other end of the said hinge link being coupled, by the vertical pin 24, to the frame of the following set of plows. The hinge link 30 is held sidewise and lateral movement prevented by guide

bars 32, carried by the frame of the leading set of plows, while the following set of plows can turn on the pin 24, and the hinge link 30 has ample vertical play to allow either set of plows to rise, or fall. By 70 this coupling it is impossible for the sets of plows to overrun, or get locked, when turning corners, and practically the whole pull of the plows is taken by the coupling ropes 28, or the like. The said vertical pin 24 has a considerable amount of play in the eye at the end of the hinge link 30, which is sometimes in tension and at other times in compression.

The lifting gear consists of a tumbling lever 33 (see Figs. 1, 2 and 7) secured by bolts to a T- or L-shaped head 34, on a shaft 35, carried by brackets 36, secured to the plow frame 2. The other end of the said tumbling lever 33 is provided with a shoe 37, slotted for the lever 33 to pass through it, the slot 38 being long enough to allow the shoe 37 to swing freely on a pin 39 which passes through the lever 33, and the carrier of the shoe 37. The shoe 37 is provided with projections, such as cross angle-irons 40, to dig into, or grip, the ground. The effective length of the said tumbling lever 33 can be altered by passing the bolts which secure it to the head 34 through different holes of a series provided for this purpose. The length of the said lever 33 determines the height to which the frame 2 is lifted. When the plows are at work, the said lever 33 is supported clear 100 of the ground, for instance by resting on a hinged catch 41 (Figs. 1 and 2). When the plows are to be lifted, the tumbling lever 33 is thrown over (in the direction of the arrow in Fig. 1) and the shoe 37 comes onto the ground, and, as the plow advances, the lever 33 turns on the center 39 and describes an arc of a circle and lifts the plow frame, provision being made for retaining it near its highest point which can be effected by the arrangement shown in Figs. 4 and 5. The lifting of the front end of the frame is done by the front wheel 3 running up the slope at the end of the furrow and bringing the front plow-shares to the surface (see Fig. 1) and the front plow cannot reenter the ground again unless this wheel drops into another furrow, or is altered vertically by the screw and nut.

Referring to Figs. 4 and 5, the aforesaid intermediate wheel 5 runs on a crank-pin 42, carried by a crank-arm and toothed sector 43, free to turn on a stud 44, fixed to the frame 2. When the frame 2 is lifted by the tumbling lever 33, the intermediate wheel 5 remains on the ground and the crank-arm and sector 43 turn on the stud 44, and the ratchet-teeth of the sector 43 pass a pawl-catch 45, on a hand lever 46, but when the frame 2 tends to fall, the sec-

1,018,262
at right angles to the said frame 2, and the said frame 2 is carried on a road by a pair of wheels 3 and 4, and a pair of wheels 5 and 6, and the said frame 2 is provided with a sector 43, and a pawl-catch 45, and a lever 46, and a sector 43 is held by the said pawl-catch 45 engaging with the ratchet-teeth of the sector 43. The said intermediate wheel 5 is the only one manipulated when lifting, or lowering, the plows in ordinary work; it also regulates the depth of the work.

When the forward wheel 3 arrives at the end of the furrow (see Fig. 1) it runs out to the surface and brings up the front plows 10 with it. The hinder wheel 4 is principally a side-thrust wheel when plowing, but it serves as a carrying-wheel when the plow is on the road in the same manner as the forward wheel 3. The intermediate wheel 15 5 is preferably placed somewhat nearer the back than the front end of the plow, and it is this intermediate wheel 5 which carries the back end of the plow frame and regulates the depth of the plowing. It is therefore necessary for this wheel to have some adjusting arrangement which may be illustrated in Figs. 4 and 5. A worm-toothed quadrant, or wheel, 47 provided with an arm 48 is mounted so as to be free to turn 20 on the stud 44, which carries the aforesaid crank and sector 43, and the worm teeth engage with a worm 49 carried by a spindle 50, turning in bearings 52, carried by the frame and provided with a handle 51. The 25 said worm-toothed quadrant, or wheel, 47 is placed immediately alongside the crank sector 43, and, being on the same stud 44, is concentric with it. The tail end of the crank pin 42 extends beyond the crank 43, and below the arm 48 on the worm-toothed 30 quadrant, or wheel, 47. When plowing, the weight of the frame 2 supported by the aforesaid intermediate wheel 5, is carried by the quadrant arm 48 resting on the crank- 35 pin 42, and the depth is adjusted by turning this arm 48 up, or down, by means of the worm 49 and quadrant, or wheel, 47. When the frame 2 is lifted, the arm 48 lifts with the frame and leaves the crank pin 42, but 40 when the plow is again lowered to its work, the arm 48 comes to rest against the crank pin 42 at exactly the same depth as before. If it be desired to alter the depth, this is 45 done by turning the worm spindle 50 so as to alter the position of the arm 48. When the plow is on the road, the frame 2 is carried on the said intermediate wheel 5 through the sector 43 and pawl-catch 45. To put the plow to work, the attendant 50 operates the lever 46 of the pawl-catch 45 so as to release the said intermediate wheel 5 and allow the plows to enter the ground till the arm 48 comes to rest again on the crank pin 42.

When subsoilers are employed in plows of this type, it is difficult to lift the said subsoilers clear of the ground, for, as already stated, the under sides of the aforesaid forward and hinder wheels 3 and 4 run approximately level with the plow-shares

when plowing, and, as these wheels 3 and 4 are not altered when the plow arrives at the end of the furrow, the plow-shares just scrape the surface of the ground when the plow is on the headland, and, as the subsoil tines extend a considerable depth below the plow-shares (see Fig. 6), provision must be made for lifting them. Referring now to Fig. 6, the forward subsoil tine 53 is carried by a bracket 54 direct from the frame 2 and the other tines are carried by brackets 55 secured to the respective plow-heads 1. There is no subsoiler immediately behind the rear plow-head, as it is desirable that the aforesaid forward and hinder 70 wheels 3 and 4 should travel on solid ground. The subsoiling of this furrow is therefore left until the following round, when the first subsoil tine 53 subsoils this furrow left by the last plow after the forward and hinder wheels 3 and 4 have passed over on firm ground.

The lifting of the subsoil tines is effected as follows by the aforesaid tumbler lever 33, which lifts the plows. Each tine 53 has teeth on one edge of its upper part 56, with which teeth engages a pinion 57 carried on a spindle 58, passing through bearings in the bracket (54 or 55) and carrying a lever 60 keyed to it. The tine 53 is held to the bracket (54 or 55) by lugs 61 (cast on the bracket) and straps 62, but is free to rise and fall. The straps 62 are secured, by bolts 63, to the bracket (54 or 55) and lugs 61. These bolts 63 at the back of the tine carry rollers 64, which take the pressure on the tine 53 when subsoiling, and less power is required to lift the tines than would be required if they passed through ordinary slots. The several tine-lifting levers 60 are connected together by a coupling rod 65 (see Figs. 6 and 7), which is connected by a pin 66 to a sector 67, which turns on a pin 68 and has a tappet arm 69, which projects toward the aforesaid tumbling lever shaft 35, the sector 67 being provided with notches 70 and 71 to receive a catch 72 on a hand lever 73. The shaft 35 of the tumbling lever 33 has a cam 74 (see Fig. 7) keyed to it and also a lever 75 which carries a roller 76. The tumbling lever shaft 35, as it is turned by the tumbling lever 33, brings the said cam 74 into contact with a plate 77, raises the catch-lever 73, and removes the catch 72 out of the notch 70 in the sector 67, and, immediately after this catch 72 is lifted, the roller 76 strikes the tappet arm 69 on the sector 67 and turns the sector 67 until the catch 72 falls into the other notch 71, at the other end of the sector 67. By this time the roller 76 has passed the face of the tappet arm 69 and the sector 67, by means of the coupling rod 65, acting through the levers 60 and pinions 57, engaging in the racks 56 on the several 80 85 90 95 100 105 110 115 120 125 130

tines 53, lifts all the tines clear of the ground and they are held in this position by the catch 72 engaging the notch 71 in the sector 67. When it is required to lower the tines 53 into the ground, the catch lever 73 is lifted by hand and the tines 53 drop to the surface of the ground and are drawn into work. If the ground be hard, the attendant, to make the tines 53 enter the ground, can operate a lever 78 carried on an extension of one of the levers 60, which lever is connected to the coupling rod 65. Each tine 53 can be provided with stop pins 79 (see Fig. 9) which can be shifted up, or down, in holes 80 in the tines 53 and rest on the lug 61 and strap 62 carried on the bracket (54 or 55) to regulate the depth of the subsoiling. As it takes considerable power to lift the subsoiler, the aforesaid roller 76 is arranged so that it does not come into contact with the tappet arm 69 of the lifting sector 67 until the shoe 37 of the tumbling lever 33 has got a good hold of the ground with the weight of the plow on the top of the lever.

Having now particularly described and ascertained the nature of my said invention and in what manner the same is to be performed, I declare that what I claim is:—

- 30 1. A plow having a frame, a surface wheel with cranked spindle pivotally supported from the frame, a stop limiting the upward travel of said crank and means for vertically adjusting said stop, for the purpose specified.
- 35 2. A plow having a frame, a surface wheel with cranked spindle pivotally supported from said frame, a stop limiting the upward travel of said crank, a worm wheel 40 controlling the position of said stop and means for actuating said worm wheel to vertically adjust the stop, for the purpose specified.
- 45 3. A plow having a frame, a surface wheel with cranked spindle pivotally supported from said frame and free to rotate on the

lifting of said frame, means for automatically holding said spindle in the position to which it is rotated by the lifting of the frame, and an adjustable stop limiting the 50 rotation of said crank in the opposite direction, for the purpose described.

4. A plow having a frame with side member, a stub shaft supported wholly by said side frame member, a surface wheel with 55 cranked spindle pivoted on said stub shaft and free to rotate upon the lifting of said frame, a ratchet rigid with said cranked spindle and rotating therewith, a pawl pivoted on said frame member and engaging 60 said ratchet to hold said crank in its lowered position, a stop limiting the upward travel of the crank, a worm wheel interposed between said ratchet and frame and controlling the position of said stop, and a worm 65 gear carried by said frame and operating said worm wheel to adjust the vertical position of said stop, for the purpose specified.

5. In a device of the character described, 70 a surface wheel with cranked spindle having limited freedom of oscillation on the frame and means to vary the extent of its oscillation, said means comprising an adjustable bearing arm pivoted to the frame and a stud on the cranked spindle bearing 75 against said bearing arm.

6. In a device of the character described, 80 a surface wheel with cranked spindle having limited freedom of oscillation on the frame and means to vary the extent of said oscillation, said means comprising a bearing arm with hand operated worm gear to control the position thereof together with a stud on the cranked spindle bearing against 85 said bearing arm.

In testimony whereof I have signed my name to this specification in the presence of two subscribing witnesses.

HENRY McLAREN.
